UNITED STATES PATENT OFFICE.

WILLIAM B. FULTON, OF MIDDLETOWN, OHIO.

CHIMNEY-BUILDING ACCESSORIES.

1,216,223.

Specification of Letters Patent. Patented Feb. 13, 1917.

Application filed December 6, 1916. Serial No. 135,514.

To all whom it may concern:

Be it known that I, WILLIAM B. FULTON, a citizen of the United States, residing at Middletown, Butler county, Ohio, have invented certain new and useful Improvements in Chimney-Building Accessories, of which the following is a specification.

This invention relates to accessories for facilitating the construction of chimneys in freezing weather and has been devised with special reference to the building of chimneys of concrete.

The invention will be readily understood from the following description taken in connection with the accompanying drawing, which is a side elevation part vertical diametrical section of an exemplification of the improved accessories at the progressing upper portion of a chimney being constructed of concrete.

In the drawing:—

1, indicates the upper end of the completed portion of the chimney:

2, the exterior form or mold:

25 3, the interior form or mold:

4, concrete being filled in on top of the completed work between the inner and outer forms:

5, trestlework extending from the base of the chimney upwardly and added to upwardly as the work progresses:

6, the cathead supported by the trestle-work:

7, a skeleton bracket-ring supported by the trestlework in position above the forms:

8, suspenders connecting the forms with the ring: and

9, the catfalls illustrated rudimentally.

All of the parts thus far referred to may

40 be of usual construction and subject to any usual appropriate modifications. In operation, the forms are supported from the cathead, the lower portions of the forms engaging the completed hardened work, and

45 green concrete is filled into the mold space and allowed to set. When the concrete is properly hard then the molds are elevated so as to form a new mold-space above the work which has hardened, the lower portion

50 of the forms still engaging the finished portion of the work. Previous to this the cathead will have been elevated and arranged for support by means of properly added trestlework. All of this is as usual

and the improvements to be described are 55 designed to provide for continuing the work in freezing weather, or weather so severely cold as to render reliable concreting impracticable under ordinary conditions of procedure. 60

Proceeding with the drawing:—

10, indicates a helical coil of pipe surrounding the outer form, the coil having at least the vertical height of the forms, the coil being formed of segments of pipe suitably united by unions to facilitate erection:

11, a curtain-ring supported above the molds, this curtain-ring being preferably formed or carried by bracket-ring 7, the curtain-ring, however formed and supported, 70 being larger in diameter than the pipe-coil:

12, a curtain-ring at the base of the coil and preferably supported by brackets from the outer form:

13, an inclosing curtain of any suitable 75 material, surrounding the coil and hanging from the upper curtain-ring and projecting below the lower curtain-ring:

14, a girdle of any suitable material and construction, surrounding the lower portion of the curtain and drawing and holding the base of the curtain against the completed portion of the chimney below the molds:

15, a steam-supply pipe, preferably a hose, extending up through the interior of the 85 chimney and connected with the coil and adapted for connection at its base with a boiler or other source of steam-supply:

16, a throttle-valve in the supply-pipe:

17, a reducing valve which may be provided, if desired, in the supply-pipe:

18, a steam gage which may be provided, if desired, in the supply-pipe.

19, a recording thermometer which may be provided, if desired, at some appropriate 95 point in the near neighborhood of the mold space being filled with concrete, the preferable location for this thermometer being in the space between the curtain and the outer form: and

20, the drain-pipe leading from the coil, the discharge end of this drain-pipe being adapted for connection with any suitable trap or tank or waste.

By means of the steam coil, the region of 105 molding may be kept at proper temperature, the curtain protecting the coil from the general atmosphere and from winds. The

coil is to be suitably supported by the trestlework, preferably through the medium of suspenders connected with the bracketing. When the forms are elevated for a new molding operation then the coil goes up with them, and at this time steam may be shut off from the coil or, if desired, the coil may be retained in use for giving comfort to the workmen.

10 The curtain 13 may be formed of any suitable substantial material, such as sheet metal and it is highly desirable that the base of the annular space formed within the curtain be closed to prevent currents of air upward through the space. This inclosure may be effected by any suitable flooring for the space, as by extending the curtain inwardly to the chimney. In practice, and in the illustrated exemplification, the curtain is of 15 textile fabric, as canvas, with its skirt gathered inwardly and joined to the chimney by the girdle 14. It is desirable that the curtain, regardless of the material of which it is constructed, extend below the outer 20 form so as to give protection to that portion of the completed work immediately below the outer form. When a section of the work has hardened and the forms have been elevated to furnish the mold space for further work, 25 the completed work off which the forms have been raised may contain such an amount of moisture that immediate exposure to the weather is undesirable. It is manifest that the base of the curtain may 30 extend so far below the outer form as to encompass all of the new work representing the last preceding molding operation.

The reducing valve, if employed, permits of an insured definite pressure in the coil reduced from an excessive pressure in the supply-pipe. If a chimney-building contract specifies that the concreting be done within certain limits of temperature, the recording thermometer, which should be kept 40 on the windward side of the structure, will serve to show the temperatures which have been prevailing at all times during the construction. While an excessive pressure of steam coming through the supply-pipe may 45 be reduced by means of the throttle valve before going to the coil, and while it may be reduced automatically by the reducing valve, if employed, it is my preference that the control of the steam to the coil be under 50 the influence of the temperature at the molding region instead of under the steam pressure, and this is accomplished by employing a reducing valve of the thermostatic type in which the flow of the steam past the valve 55 is controlled by the temperature in the neighborhood of the valve.

While the invention has been devised with special reference to the building of concrete chimneys, it is available in the building of 60 analogous concrete vertical structures such,

for instance, as tanks and silos, and the term "chimney" as herein used is to be considered in its broad sense.

I claim:—

1. Chimney-building accessories comprising, rigging supported over a concrete chimney under construction, a mold-part supported by such rigging with its base in contact with a completed portion of the work and adapted to define the exterior form of the chimney, a mold-part similarly supported and adapted to define the interior form of the chimney, a curtain supported from said rigging and surrounding the exterior mold-part but at a distance outwardly therefrom, a helical coil of pipe surrounding the exterior mold-part within the space between it and the curtain, and a steam-supply pipe leading up within the interior of the chimney and connected with the coil, combined substantially as set forth. 75 80 85

2. Chimney-building accessories comprising, rigging supported over a concrete chimney under construction, a mold-part supported by such rigging with its base in contact with a completed portion of the work and adapted to define the exterior form of the chimney, a mold-part similarly supported and adapted to define the interior form of the chimney, a curtain supported from said rigging and surrounding the exterior mold-part but at a distance outwardly therefrom, means for flooring the annular space within the curtain, a helical coil of pipe surrounding the exterior mold-part within the space between it and the curtain, and a steam-supply-pipe leading up within the interior of the chimney and connected with the coil, combined substantially as set forth. 90 95 100

3. Chimney-building accessories comprising, rigging supported over a concrete chimney under construction, a mold-part supported by such rigging with its base in contact with a completed portion of the work and adapted to define the exterior form of the chimney, a mold-part similarly supported and to define the interior form of the chimney, a curtain supported from said rigging and surrounding the exterior mold-part but at a distance outwardly therefrom, means securing the base of the curtain in inward position so as to close the base of the space between the curtain and the exterior mold-part, a helical coil of pipe surrounding the exterior mold-part within the space between it and the curtain, and a steam-supply-pipe leading up within the interior of the chimney and connected with the coil, combined substantially as set forth. 105 110 115 120

4. Chimney-building accessories comprising, rigging supported over a concrete chimney under construction, a mold-part supported by such rigging with its base in contact with a completed portion of the work and adapted to define the exterior form of 125 130

the chimney, a mold-part similarly supported and adapted to define the interior form of the chimney, a flexible curtain supported from said rigging and surrounding the exterior mold-part but at a distance outwardly therefrom and gathered inwardly at its base into contact with the completed work below the exterior mold-part, a girdle securing the base of the curtain against the completed work, a helical coil of pipe surrounding the

exterior mold-part within the space between it and the curtain, and a steam-supply-pipe leading up within the interior of the chimney and connected with the coil, combined substantially as set forth.
